UNITED STATES PATENT OFFICE.

JOHN K. GRAHAM AND GEORGE RASMUSSEN, OF ROANOKE, VIRGINIA.

METAL-PUNCHING MECHANISM.

1,178,797.

Specification of Letters Patent. Patented Apr. 11, 1916.

Application filed June 12, 1915. Serial No. 33,654.

To all whom it may concern:

Be it known that we, JOHN K. GRAHAM and GEORGE RASMUSSEN, respectively a citizen of the United States and a subject of the German Emperor, residing in the city of Roanoke, county of Roanoke, and State of Virginia, have invented certain Improvements in Metal-Punching Mechanism, of which the following is a specification.

10 Our invention relates to mechanism for punching metal such as is used in structural work, and our primary object is to facilitate the operations of punching sheets, shapes and the like so that the same shall be done 15 accurately and rapidly by automatically controlled multiple punches.

The characteristic idea of our invention resides in novel means comprising a master form or templet, multiple punches, and 20 mechanism comprising electric circuits controlled by the movements of said templet for controlling the actions of said punches.

The invention is fully disclosed in the following description and the accompanying 25 drawings in illustration thereof.

In the drawings, Figure 1 is a broken front elevation of a part of a machine embodying our invention; Fig. 2 is a vertical sectional view taken on the line 2—2 of Fig. 30 1; Fig. 3 is a broken vertical sectional view on an enlarged scale of a second position of details of the construction shown in Fig. 2; Fig. 4 is a broken end elevation of the templet carrying mechanism combined with 35 the circuit controlling mechanism controlled by the templet; Fig. 4^a is a broken plan view of circuit controlling mechanism; Fig. 5 is a broken front elevation of the construction shown in Fig. 4; and Fig. 6 is a diagrammatic view of the wiring system with mechanism combined therewith.

The invention, in the form thereof illustrated in the drawings, comprises a housing 1 provided with the reciprocatory head 2, which carries a desired number of punches 3 adapted to reciprocate in the guides 4 fixed to the bottom of the head, and the revolute eccentric or crank shaft 5, which is connected with the head by means of the pitman 6 to effect the desired reciprocating movement of such head. Anvils 7 are provided with the die blocks 8 on which is held the work 9 to be punched, upon the descent of the head 2, by selected punches 3 which are rendered operative through the action of the master mechanism.

The master mechanism comprises independently operating slides 10 which are adapted to be reciprocated in ways 11 in the bottom of the head 2 and above the 50 respective punches. The slides are thrust in to prevent downward movement of the head on or independently of the punches which should be driven through the work, and are retracted to permit the head to move downward independently of the punches that should remain inoperative in the downward movement of the head. The slides 10 are adapted to be reciprocated independently by the respective levers 12 which are fulcrumed on bearings 13 fixed to the head, the levers being provided with the longitudinally adjustable stems 12^a having flexible connections with the stems 10^a of the slides.

Each lever 12 is provided with a bearing 12^b, which supports a solenoid coil 11' having an armature 11^a, and with a bearing 12^c on which is fulcrumed a lever 14 pivotally connected to the armature. Each lever 12 is also pivotally connected to a rod 15, which is provided with the adjustable stops 15^a on opposite sides of the bearing 12^b to contact therewith for limiting the reciprocations of the rod, the latter reciprocating through and being controlled by the bearing or guide 12^d on the lever 12 as well as by the bearings 12^b and 12^c.

The head 2 is further provided with the forwardly extending guides 16 on which is mounted a bar 17 adapted to be reciprocated to and from the head across the lines of the rods 15 in their positions when the slides 10 are drawn back, the bar being adapted for engaging the respective rods 90 when elevated by the armatures for the purpose of rocking the levers 12 and moving in the slides 10 to positions directly above the punches 3.

The bar 17 is reciprocated on the guides 16 in synchronous relation to the reciprocations of the head 2 by providing the shaft 5 with cams 18 which engage crank levers 19 through their roller 19^a; these levers being fulcrumed by means of a rod 20 carried by the housing 1, connected with the bar 17 by the links 21 and connected by a bar 22 adapted for engaging the tops of the levers 12.

A frame 23 is fixed to the housing 1 and 110 has journaled therein the top roller 24 (on which is rolled the paper pattern or templet

25 at the beginning of the operation), the bottom roller 26 (onto which the pattern is wound from the roller 24 during the operation), the intermediate feed roller 27 (having sprockets 27^a for engaging the edge perforations 25^b of the pattern), the intermediate guide rollers 28 (on opposite sides of the roller 27), and the tracker roller 29 provided with circular channels 29^a (with which the pattern's perforations 25^a register); the roller 24 being provided with a handle 24^a for rewinding, the rollers 26 and 27 being connected by the belt 30 to effect their coordinate action and the roller 27 having a driving ratchet 27^b fixed on its journal 27^c, whereby the pattern is carried forward.

10 A lever 31 is fulcrumed on the journal 27^c, carries a pawl 31^a for driving the ratchet 27^b, and is oscillated synchronously with the reciprocation of the head 2 by a lever 32 having a fulcrum 32^a on the housing 1, a pivotal connection 32^b with the head, and a link connection 33 with the lever 31.

15 Contact levers 34, corresponding to the respective grooves 29^a, are fulcrumed on a bar 35 of the frame 23. The levers have thereon the rollers 34^a, which are adapted to ride on the pattern 25 as it passes around the roller 29 and to pass through the registering perforation 25^a into the groove 29^a, and are provided with the weights 34^b for elevating the rollers. A cam bar 36, operated by the handle 36^a, serves to elevate the levers 34 and disengage the rollers 34^a from the pattern 25. Insulated contact pins 37 are held adjustably in the bearing 38 of the frame in position to be engaged by the levers 34 when their weighted ends fall, upon the passage of their rollers 34^a through the perforations 25^a of the pattern 25.

20 The respective levers 34 and contact pins 37 are in circuit with the respective solenoid or electro-magnet coils 11'. Each lever 34 is connected by a conductor 39 with a contact 40 supported by the housing yoke 1^a, the contact 40 being adapted for engagement by a contact 41 of a lever 42 which is fulcrumed on the yoke 1^a and moved from its normally disengaged position by a cam 5^b set on the shaft 5 to control the circuits 45 so as to prevent sparking. The contact 41 is connected by a conductor 42^a with a switch 43 through which current is admitted, and the switch is connected by a conductor 44 with the respective solenoids 11'. Each solenoid 11' is connected by a conductor 45 with a binding post 46 on the frame 23 and through the binding post by conductors 47 with the respective contacts 37.

25 In operation, the pattern 25, which is perforated to scale proportionate to the sheet or shape to be punched, is moved from the roller 24 onto the roller 26, over the rollers 27, 28 and 29, in synchronism with the reciprocations of the head 2, by the action of the latter through the parts 32, 33, 31, 31^a and

27^b. When the body of the pattern engages rollers 34^a, the corresponding levers 34 are held thereby out of engagement with the contacts 37, the corresponding circuits are thereby held open, the solenoids 11' are inactive, and their armatures 11^a are elevated by the weight of the rods 15^a, the latter falling automatically out of the path of the bar 17. As the bar 17 is reciprocated on the guides 16 (by the cams 5^a acting through the parts 19 and 21) it will not affect the levers 12 whose rods 15^a are down, in which position the slides 10 are withdrawn, due to the action of the bar 22 on the levers. Hence the head 2 will move down on the corresponding punches 3, which are thus inoperative. But when a roller or rollers 34^a register with perforations 25^a of the pattern, the weighted arms of the levers 34, corresponding to such rollers, drop into engagement with the corresponding contact pins 37 and close the circuits containing the corresponding electro-magnetic or solenoid coils 11'. These coils 11', thus excited by the closure of their circuits, draw in their armatures 11^a, which act through the corresponding levers 14 to elevate the respective rods 15 into the path of the bar 17. Hence when this bar 17 is drawn back (by the action of the cams 5^a through the parts 19 and 21) it acts on the elevated rods 15 to rock the corresponding levers 12 and thrust in the slides 10 above the respective punches 3, which are thereby supported so that upon the descent of the head 2 such selected punches are forced through the metal 9.

30 Having described our invention, we claim:

1. In a metal punching machine, the combination of a set of punches adapted to reciprocate independently, independently movable bearings for the respective punches, normally disengaged devices for moving said bearings, a pattern, and means comprising electric circuits closed through said pattern for selectively effecting the engagement of the devices for operating the respective bearings.

nisms for reciprocating the respective devices, lever mechanisms for reciprocating the respective lever mechanisms first named, a pattern, and electrical means whereby said 5 pattern effects selective engagements of lever mechanisms first named and lever mechanisms second named.

4. In a metal punching machine, the combination of a reciprocating head, punches carried by and having a limited movement relative to said head, devices carried by said head for controlling the relative movements between said head and the respective punches, mechanisms for mechanically operating said 10 devices, a pattern, adapted for controlling an electric circuit, means whereby said pattern is moved in coordination with the reciprocation of said head, and means comprising an electric circuit whereby said pattern controls selectively operative engagements between the respective mechanisms and devices.

5. In a metal punching machine, the combination of a reciprocating head, punches carried by and having a limited movement relative to said head, reciprocating devices carried by said head to provide removable bearings for the respective punches, a pattern, means for carrying said pattern, means 25 operated by said head for moving said pattern, and means comprising an electric circuit whereby said bearings are operated and the respective punches are controlled.

6. In a metal punching machine, a reciprocating member, a punch carried by and having a limited movement of reciprocation relative to said member, a device carried by and movable relative to said member to provide a bearing for said punch, a lever 30 carried by said member whereby said device is movable into and out of cooperative relation with said punch, a pattern, and means comprising a circuit containing an electro-magnet for rocking said lever.

45 7. In a metal punching machine, a reciprocating head, a punch carried by and having a limited movement relative to said head, a reciprocating bearing carried by said head for holding said punch, a lever carried by said head and connected with said bearing to effect its reciprocation, a reciprocating member carried by said lever, means comprising an electro-magnet for moving said member, a revoluble shaft, means whereby said shaft 50 reciprocates said head, means whereby said shaft acts through said member to rock said lever, a pattern, and means controlled by said pattern for controlling said electro-magnet.

60 8. In a punching machine, a housing, a head adapted to reciprocate in said housing, multiple punches carried by said head and respectively adapted to reciprocate therein, sliding bearings carried by said head and 65 adapted to be operated independently to

limit the relative movement between said head and the respective punches, levers fulcrumed on said head and connected with the respective bearings to effect their reciprocations, members carried by the respective levers and adapted to reciprocate relatively thereto, a shaft movable in said housing, means whereby said shaft effects the reciprocation of said head, means comprising a reciprocating device operated by said shaft 70 for engaging said members, said members being movable into and out of position for engagement by said reciprocating device, means comprising electro-magnets for operating said members, and means comprising 75 a pattern for selectively exciting said electro-magnets.

9. In a metal punching machine, a perforated pattern, means comprising a roller containing channels over which said pattern 80 is carried with perforations thereof in registration with respective channels, reciprocating devices adapted to bear against said pattern and to enter said channels through respective perforations of said pattern, electro-magnetic mechanism comprising circuits controlled by said devices, reciprocating punches, and means operated selectively by said electro-magnetic mechanism for controlling the movements of said punches.

10. In a metal punching machine, a pattern, means for translating said pattern, contact levers controlled by said pattern, circuits containing electro-magnets controlled by said levers, a set of independently 100 movable punches, and means acting under control of said electro-magnets for controlling the actions of said punches.

11. In a metal punching machine, a perforated pattern, means comprising a recessed device with which perforations of said pattern are adapted to register, circuits comprising electro-magnets and reciprocating circuit closers adapted to enter the recesses of said device through the perforations of said pattern, armatures adapted to be operated by said electro-magnets, levers whereby said electro-magnets and armatures are carried, a plurality of independently movable punches, means operated by said levers for controlling said punches, and means comprising devices operated by said armatures for operating said levers.

12. In a metal punching machine, a reciprocating head, punches having limited movements of reciprocation in said head, devices adapted to slide in said head transversely to said punches to hold the same, levers fulcrumed on said head and connected with said devices to effect their reciprocation, electro-magnets carried by the respective levers, armatures adapted to be operated by the respective electro-magnets, reciprocating rods carried by the respective levers and connected with the respective ar- 120 125 130

matures whereby they are operated, guiding means carried by said head, reciprocating means carried by said guiding means for engaging said rods and rocking said levers, a 5 revoluble shaft, means whereby said shaft reciprocates said head and means whereby said shaft operates said reciprocating means.

13. In a metal punching machine, a housing, a shaft journaled in said housing, a head, means whereby said shaft reciprocates said head, a set of punches respectively adapted to move in said head, sliding devices carried by said head to provide bearings for the respective punches, levers fulcrumed on said head and connected with said sliding device to effect their reciprocation, electromagnets carried by the respective levers, guiding means carried by said head, mechanism adapted to reciprocate on said guiding means, devices carried by said levers and operated by said electro-magnets whereby said mechanism operates said levers, a cam on said shaft, and means whereby said cam operates said mechanism.

14. In a metal punching machine, a reciprocating punch, a reciprocating device

adapted to provide a bearing for supporting said punch, a fulcrumed lever connected with said device to move it into and out of position for holding said punch, a reciprocating rod on said lever, means comprising an electro-magnet for operating said rod, a reciprocating device for engaging said rod to operate said lever, a pattern, and means whereby said pattern controls the action of said electro-magnet.

15. In a metal punching machine, a housing, a head adapted to reciprocate in said housing, punches carried by said head and adapted to move relatively thereto, devices adapted to reciprocate in said head to provide bearings for said punches, means comprising circuits containing electro-magnets for operating said devices, a perforated pattern, means operated by said head for translating said pattern, and a set of contact levers controlled by said pattern whereby said circuits are controlled.

In testimony whereof we have hereunto set our names this tenth day of June, 1915.

JOHN K. GRAHAM.
GEO. RASMUSSEN.
